[57] CLAIM

The ornamental design for a computer adapter for use in a least telephone call routing system, as shown and described.

DESCRIPTION

FIG. 1 is a perspective view of a computer adapter for use in a least cost telephone call routing system showing the new design, the broken lines showing an indentation, computer connectors and telephone connectors are for illustrative purposes only and are not part of the design sought to be patented;

FIG. 2 is a top view of the computer adapter for use in a least cost telephone call routing system;

FIG. 3 is a bottom view of the computer adapter for use in a least cost telephone call routing system;

FIG. 4 is a front view of the computer adapter for use in a least cost telephone call routing system;

FIG. 5 is a rear view of the computer adapter for use in a least cost telephone call routing system;

FIG. 6 is a left side view of the computer adapter for use in a least cost telephone call routing system; and,

FIG. 7 is a right side view of the computer adapter for use in a least cost telephone call routing system.
